UNITED STATES PATENT OFFICE.

CHARLES F. STEHLIN, OF NEW ROCHELLE, NEW YORK.

COPY-HOLDER.

No. 910,968.

Specification of Letters Patent.

Patented Jan. 26, 1909.

Application filed April 15, 1908. Serial No. 427,245.

To all whom it may concern:

Be it known that I, CHARLES F. STEHLIN, a citizen of the United States, residing at New Rochelle, in the county of Westchester, 5 State of New York, have invented new and useful Improvements in Copy-Holders, of which the following is a specification.

My invention relates to copy holders, and has for its object to provide certain improvements in the construction and operation of the same as will be hereinafter more definitely pointed out and claimed, reference being had to the accompanying drawings, in which:

15 Figure 1 is a side elevation of my improved device. Fig. 2 is a top plan view of the base of the device and its parts. Fig. 3 is a front elevation of the device. Figs. 4 and 5 are enlarged detail views of modified forms of 20 support for the line guide arm. Fig. 6 is an enlarged detail sectional view of the friction retarding disk and its support.

Similar numerals of reference denote corresponding parts in the several views.

25 In the said drawing the reference numeral 1 denotes the base or support of the device, from which rises centrally a standard 2 adapted to telescopically receive an extension rod 3 that is flattened at its upper end to 30 pass between ears or lugs 4 fixed to the rear side of the copy supporting plate 5, a suitable set-screw 6 passing through said ears and rod to clamp said plate 5 in any adjusted position. Said standard 2 may be split at 7 at its upper 35 end, whereby, through a suitable collar 8 and lever 9, the rod 3 may be adjustably clamped therein.

Supported from the upper and lower corners of the plate 5 at one side thereof, 40 through arms 10, are two parallel guide rods 11, said arms 10 being connected to segmental plates 12 riveted or otherwise fixed to said plate 5 on its rear side, as shown in dotted lines, Fig. 3. Fixed to the upper arm 45 10 is a bracket 13 in which is rotatably mounted a grooved wheel 14.

Mounted to slide freely on the rods 11 is a carrier 15 for the line guide arm 16, said carrier having upper and lower plates 17 that 50 are apertured to engage said rods 11, as shown. The line guide arm 16 is pivoted to said carrier to swing to a vertical position, its pivot pin 18 fixed to carrier 15 being

elongated to permit a bodily adjustment of said line guide arm 16 thereon towards and 55 from the plate 5. A suitable stop 19 on the carrier 15 limits the movement of arm 16 in one direction and retains it in horizontal alinement across the plate 5, while another stop 20 limits the movement of said arm 5 60 when swung on its pivot to a vertical position.

Extending across the top of the plate 5 is a copy retaining bar 21, having its bent ends 22 pivoted to opposite sides of said plate 5 65 at 23, one of said ends 22 being extended, then bent horizontally at 24 across the back of said plate 5, and then curved downwardly and outwardly at 25, where it terminates in a counter-weight 26. 70

At the bottom of plate 5 is a copy retaining bar 27 similar to bar 21, and having its bent ends 28 pivoted to the plate 5 at 29, one of said ends 28 being extended and provided with a knife edged portion 30 adapted to engage toothed portions 31 at the upper or lower ends of a segment 32 supported from plate 5. 75

Mounted in standards 33 rising from the base 1 is a horizontal shaft 34 carrying at its 80 opposite ends the grooved wheels 35 and 36. Fixed to said wheel 35 is a cord 37 adapted to be wound thereon, the same passing upwardly over wheel 14 and thence downwardly to carrier 15, to which it is connected. 85 The wheel 36 has fixed thereto a chain or cord 38 adapted to be wound thereon in a direction opposite to that of cord 37 on wheel 35, said chain or cord passing from said wheel through a curved guide tube 39 to 90 the front of the device, where it terminates in a knob or handle 40 that is too large to pass into guide 39. Mounted in a spring arm 41 rising from the base 1 is a screw-shaft 42 having an adjusting thumb piece 43, and carrying at its other end a friction button 44 loosely mounted on said shaft 42, as shown in Fig. 6, and adapted to be brought, through the resiliency of spring arm 41, into contact with the side of wheel 36 to act as a friction brake thereon and on shaft 34 and its parts. 95

Pivoted at 45 in a bearing 46 on the base 1 is a lever 47, having its outer end preferably telescoping as shown to adjustably vary the 100 length thereof, and terminating in a key 48.

The inner end of said lever is connected, by means of a link 49, with a pawl 50 pivoted at 51 to a bar 52 that is in turn pivoted on the shaft 34. Said bar 52 is provided on one side 5 with a stop 53, and is formed with a downward extension 54 that normally contacts with the base 1. Fixed to the shaft 34 is a wheel 55 with which the pawl 50 is adapted to engage when lifted by lever 47, as more 10 fully hereinafter described. The inner end of lever 47 is normally pressed downward by a coiled spring 56 and, if desired, the action of the latter may be supplemented by a leaf spring 57, as will be readily understood. 15 Mounted in an extension 58 of bearing 46 is a stop screw 59, the same lying in the path of vertical movement of the inner end of lever 47 and thereby limiting its stroke, which may be varied by adjusting said screw vertically in extension 58.

From the above description the operation of my improved construction will be understood as follows: With the line guide arm 16 in the position shown in Fig. 3, the weight of 25 the same and its carrier 15 is exerted on the cord 37 and through wheel 35 upon the shaft 34, but this tendency of the parts 15 and 16 to drop to their lowermost position is resisted by the friction button 44 pressing 30 against the side of wheel 36, the tension thereof being adjustably regulated by screw shaft 43. Now, when it is desired to feed the arm 16 downward the distance of a line of the copy supported on the plate 5, the key 35 48 of the lever 47 is depressed by the operator, which raises the inner end of said lever, and through link 49 initially tilts pawl 50 on bar 52, so that said pawl instantly engages the toothed wheel 55. The further movement 40 of lever 47 lifts pawl 50 and bar 52 on the shaft 34 as a center, whereby toothed wheel 55 and shaft 34 are correspondingly rotated, and said rotation by unwinding cord 37 on wheel 35 permits a corresponding 45 downward movement to carrier 15 and arm 16, which thus becomes a combined gravity and positive step by step feed that is checked by the spring-pressed button 44. To accommodate the step by step feed of arm 16 50 to different widths of lines on different copy, I provide the set-screw 59, which by its adjustment will vary the stroke of lever 47. It will be observed that upon the release of key 48 and the return of lever 47 to its normal 55 position, the extension 54 of bar 52 by contacting with base 1 will check the movement of said parts on the shaft 34 as a pivot, and pawl 50 will then rotate independently on its pivot 51 until it contacts with stop 53 on 60 bar 52, which will bring said pawl just out of engagement with toothed wheel 55. When the arm 16 has reached its downward limit of movement, it may be instantly elevated to its uppermost position by pulling on chain 65 38, which by unwinding from wheel 36 will

rotate shaft 34 to wind up cord 37 on wheel 35, and thereby elevate parts 15 and 16, it being observed that during this movement the pawl 50 is out of engagement with toothed wheel 55, thereby offering no resistance to said movement. 70

By providing the elongated pivot pin 18 for the arm 16, the latter is freely movable bodily thereon towards and from the carrier 15, whereby it will adjust itself automatically 75 to different thicknesses of copy held on the plate 5, and will not only lie flat against the surface of said copy, even when the latter is quite bulky, but will also ride freely over projections in said copy caused by folds 80 therein, as will be readily understood.

The normal operation of the copy retaining bars 21 and 27 will be readily understood, the bar 21 being retained against the copy by the counter-weight 26, while the bar 27 85 is more positively retained by the engagement of the knife edge 30 on one bent end 28 thereof with the upper series of teeth 31 on segment 32, the pressure of bar 27 on the copy being thus capable of variation by 90 shifting the knife edge 30 in its relation to the series of teeth 31 on segment 32. It is frequently necessary to support short sheets of copy on the plate 5, and this is readily provided for by shifting counter-weight 26 to its 95 uppermost position, which will swing bar 21 on its pivots 23 to the position shown in dotted lines in Fig. 3, and by disengaging knife edge 30 from the upper series of teeth 31 on segment 32, and bringing it into engagement 100 with the lower series of teeth thereon, which will swing bar 27 on its pivots 29 to the position shown in dotted lines in Fig. 3, thereby materially shortening the distance between said bars 21 and 27. If desired, the counter-weight construction for 105 bar 21 may be replaced by the knife edge and toothed segment construction of bar 27.

In Fig. 4 I have shown a slightly modified construction of support for the carrier and line guide arm, the rods 11 being replaced by a flat bar 60, and the carrier 15 by a carrier 61 shaped to embrace said bar, as shown, said carrier being provided with stops 62 and 63 to limit the horizontal and vertical 115 movements of the line guide arm. Again in Fig. 5 the carrier support 64 is still differently shaped, the carrier being in the shape of a sleeve 65. Furthermore, in this construction the line guide arm 66 is mounted to swing horizontally away from the plate 5, instead of vertically, as in the other figures, and to provide for its bodily movement toward and from the plate 5 I provide it with a double hinge 67, the operation of 120 which will be obvious. In said construction I also provide upper and lower stops or guides 68 to maintain said arm in a horizontal position. 125

Having thus described my invention, what 130

I claim as new and desire to secure by Letters Patent is:

1. In a copy holder, a movable gravity feed line guide, means for controlling the movement of said line guide, means for frictionally checking said controlling means, and means for positively moving said controlling means step by step against said frictional check.
- 10 2. In a copy holder, a movable gravity feed line guide, means for controlling the movement of said line guide, means for frictionally checking said controlling means, means for positively moving said controlling means step by step against said frictional check, and means for moving said controlling means in the opposite direction against said frictional check.
- 20 3. In a copy holder, a movable line guide, a shaft, a cord connecting said line guide and shaft whereby the vertical movement of said line guide is controlled by the rotation of said shaft, a friction member normally checking the rotation of said shaft, and a pivoted lever for imparting a positive step by step movement to said shaft against said frictional check to permit said line guide to move step by step downward.
- 30 4. In a copy holder, a vertically movable line guide, a rotatable shaft, a cord connecting said line guide with said shaft in such manner that the rotation of said shaft will control the position vertically of said line guide, a friction member for normally checking the rotation of said shaft, and a pivoted lever normally out of engagement with said shaft but adapted, when moved, to engage and rotate said shaft a predetermined distance, thereby similarly permitting said line
- 40 guide to move downwardly.
5. In a copy holder, a vertically movable line guide, a rotatable shaft, a cord connecting said line guide with said shaft in such manner that the rotation of said shaft will control the position vertically of said line guide, a friction member for normally checking the rotation of said shaft, means for rotating said shaft step by step against said frictional resistance to permit said line guide
- 45 to move downwardly step by step, and a second cord adapted to wind on said shaft reversely to the winding of said line guide cord for rotating said shaft to lift said line guide to any desired elevated position.
- 55 6. In a copy holder, a vertically movable line guide, a rotatable shaft, a cord connecting said line guide with said shaft in such manner that the rotation of said shaft will control the position vertically of said line guide, a friction member for normally checking the rotation of said shaft, a pivoted lever normally out of engagement with said shaft but adapted, when moved, to engage and rotate said shaft a predetermined distance, thereby similarly permitting said line guide to move
- 50 downwardly, and a second cord adapted to wind on said shaft reversely to the winding of said line guide for rotating said shaft to lift said line guide to any desired elevated position.
- 70 7. In a copy holder, a vertically movable line guide, a shaft for controlling the position vertically of said line guide, means for operating said shaft step by step to similarly permit said line guide to move downwardly, and a friction member for normally maintaining said shaft against rotation and embodying a spring supporting arm, a screw shaft adjustably engaging said arm, and a friction button loosely carried by said screw shaft and adapted to contact with an integral part of said shaft and to seat there against.
- 75 8. In a copy holder, a copy holding plate, a vertically movable line guide carrier, a line guide arm pivoted to said carrier so as to freely swing from a horizontal to a vertical position parallel with said copy holding plate, and stops on said carrier for limiting the movement of said line guide arm.
9. In a copy holder, a copy holding plate, a line guide carrier, a line guide arm, means for mounting said arm on said carrier so as to permit a free bodily movement towards and from said carrier, and means for maintaining said line guide arm in horizontal alignment under said movement.
10. In a copy holder, a copy holding plate, a vertically movable line guide carrier, and a line guide arm pivoted to said carrier and having an independent bodily movement on said pivot towards and from said carrier and line guide plate.
- 100 11. In a copy holder, a copy holding plate, and a copy retaining bar pivoted to said plate and adapted to be shifted on its pivot to engage the same side of said plate at different points.
- 115 12. In a copy holder, a copy holding plate, a transverse copy retaining bar having bent ends pivoted to said plate whereby said bar may be turned on said pivots to contact with said plate at different points, and means for retaining said bar in contact with said plate in either of its adjusted positions.
13. In a copy holder, a copying holding plate, a transverse copy retaining bar having bent ends pivoted to said plate whereby said bar may be turned on said pivots to contact with said plate at different points, an extension on one of said bent ends of said bar, and a toothed segment for engaging said extension under either position of contact of said bar with said plate to adjustably retain said bar in contact with said plate.
- 120 14. In a copy holder, a copy holding plate, an upper transverse copy retaining bar having bent ends pivoted to said plate, an extension on one of said bent ends, a counterweight on said extension adapted to retain said bar in contact with said plate, a lower
- 125 130

copy retaining bar having bent ends pivoted to said plate, an extension on one of said bent ends, and a toothed segment with which said extension is adapted to engage to adjustably retain said lower bar in contact with said plate.

In testimony whereof, I have hereunto set

my hand in the presence of two subscribing witnesses.

CHARLES F. STEHLIN.
